Primary Examiner — Martie K Holtje*(74) Attorney, Agent, or Firm* — Saul Ewing LLP(57) **CLAIM**

The ornamental design for a watch, as shown and described.

DESCRIPTION

FIG. 1 is a top plan view of a watch showing my new design in a right-handed configuration;

FIG. 2 is a bottom plan view of FIG. 1;

FIG. 3 is a rear elevational view of FIG. 1;

FIG. 4 is a front elevational view of FIG. 1;

FIG. 5 is a top right side perspective view of FIG. 1;

FIG. 6 is a left side elevational view of FIG. 1;

FIG. 7 is a right side elevational view of FIG. 1;

FIG. 8 is a top plan view of a second embodiment of my design of FIG. 1 shown in a left-handed configuration;

FIG. 9 is a bottom plan view of FIG. 8;

FIG. 10 is a rear elevational view of FIG. 8;

FIG. 11 is a front elevational view of FIG. 8;

FIG. 12 is a top left side perspective view of FIG. 8;

FIG. 13 is a left side elevational view of FIG. 8; and,

FIG. 14 is a right side elevational view of FIG. 8.

The structural features depicted by broken lines in FIGS. 2, 3, 9 and 10 have been shown for the purpose of illustrating portions of the watch that form no part of the claimed design.
